UNITED STATES PATENT OFFICE.

GROVER C. POLSON, OF BERKELEY, CALIFORNIA.

MULTIPLE-PANEL-LOCKED CABINET.

Application filed July 5, 1921. Serial No. 482,450.

To all whom it may concern:

Be it known that I, GROVER C. POLSON, a citizen of the United States, residing at Berkeley, in the county of Alameda and State 5 of California, have invented a new and useful Multiple-Panel-Locked Cabinet, of which the following is the specification.

This invention relates to display cabinets.

It is the object of the present invention 10 to provide a generally improved and simplified form of display cabinet containing a plurality of display trays or panels which may be optionally locked either in or out of an accessible position.

15 The invention contemplates the use of a cabinet containing a plurality of display trays or panels which may be shifted from a concealed position within the cabinet to an accessible position in a display opening, 20 the structure also embodying a lock mechanism whereby the panels may be locked in or out of an accessible position within the display opening.

One form which the invention may assume is exemplified in the following description and illustrated by way of example in the accompanying drawings, in which:

Fig. 1 is a front elevation of the preferred embodiment of the invention.

30 Fig. 2 is a vertical section taken on line 2-2 of Fig. 1.

Fig. 3 is a fragmentary view in perspective of the locking mechanism employed.

Fig. 4 is a side elevation.

35 Fig. 5 is a plan section taken on line 5-5 of Fig. 1.

Referring more particularly to the drawings, 10 generally indicates a cabinet or case of suitable construction and design. 40 Formed in the front thereof, adjacent one end, is a display opening 11 as shown in Fig. 1.

45 Slidably mounted in the cabinet are a plurality of display trays or panels 12 which are guided for movement longitudinally of the cabinet by guide rails 13 formed in the cabinet at the top and bottom thereof. The upper and lower ends of the panels are disposed between said rails as clearly illustrated in Fig. 2. Formed in the lower edge 50 of each display panel and adjacent one end thereof is a notch 14. The notch 14 of each panel aligns with a locking pin 15 when the panels are disposed in the position disclosed in Fig. 5. These locking pins are secured at one end of a trigger 55

member 16 which is pivotally mounted in the cabinet as at 16a. As shown in Fig. 1, the trigger member is mounted immediately below a false bottom section 17 of the cabinet, which false bottom section is apertured as at 18 to permit the locking pins 15 to pass therethrough as shown in Fig. 3.

The trigger member 16 is adapted to be actuated by the keeper of a barrel lock 19. 65 This lock is secured in the end of the cabinet as shown in Fig. 1 and in a position permitting the end 20 of the trigger to rest thereon. Therefore, when the keeper of the lock is actuated the trigger will be rocked on 70 pivot pins 21 and move the locking pins 15 in or out of engagement with the notches 14 as the case may be.

For maintaining the end of the trigger 16 in engagement with the lock a spring member 22 is provided. This spring is secured to the under side of the false bottom section 75 17 and engages the trigger 16 as shown at 23.

The display panels 12 may be equipped 80 with hooks 24 or similar elements upon which articles to be displayed may be secured to maintain them in position on the panels.

In actual practice it has been found that 85 cabinets constructed as described are extremely useful in class rooms or laboratories of educational institutions, where each student is provided with a locker or compartment. Each of the various classes of students meeting in the laboratory at different 90 periods may keep their keys on one of the panels. As the cabinet may be locked, the instructor may display each class's panel just before the class assembles and maintain 95 the other panels locked within the cabinet, thereby permitting each class access to their own keys only.

In operation, the device is assembled as 100 shown in the drawings. For the purpose of illustration it will be assumed that the display panels are in the position as shown in Fig. 5, and that the keeper of the lock is withdrawn. In this case the locking pins 13 would be in engagement with the notches 105 14 and consequently the panels would be locked against movement and out of register with the display opening 11.

To release the panels a key is inserted in the lock 19 and turned until the lock keeper 110 is ejected. This rocks the trigger member 16 as described and removes the locking

pins 13 from engagement with the recesses 14. The desired panel may then be shifted in register with the display opening 11. The key may then be turned to withdraw the keeper of the lock and consequently release the trigger. The end of this member carrying the locking pins is then forced upwardly by the spring 22 until the pins engage the notches 14, thereby locking the panels from movement.

It should be stated the locking pin for the panel shifted into register with the display opening obstructs the path of said panel and prevents movement thereof until the lock has been actuated.

While I have shown the preferred form of my invention, it is to be understood that various changes in the construction, combination and arrangement of parts may be made by those skilled in the art, without departing from the spirit of the invention as claimed.

Having thus described my invention, what I claim and desire to secure by Letters Patent is:

1. A display cabinet comprising a case, a plurality of display panels mounted in said case, means whereby said panels may be shifted from a concealed position within the cabinet to an accessible position within the cabinet, and key actuated means for securing said panels in a set position.

2. A display cabinet comprising a case having a display opening formed therein, a plurality of display panels mounted in said cabinet, means whereby said panels may be shifted from a concealed position within the cabinet into register with said opening, and means adapted to be actuated by a key controlled lock for securing said panels in a set position.

3. A display cabinet comprising a case having a display opening formed therein, a plurality of display panels mounted in said cabinet, means whereby said panels may

be optionally concealed within said cabinet or placed in register with said opening, and means adapted to be actuated by a key controlled lock for locking said panels in a set position.

4. A display cabinet comprising a case having a display opening formed therein, a plurality of display panels mounted in said case, means whereby said panels may be optionally concealed within the cabinet or placed in register with said opening, a key actuated lock, and means actuated thereby and adapted to engage each panel for securing the same in a set position.

5. A display cabinet comprising a case having a display opening formed therein, a compartment in said case adjacent said opening, a plurality of display panels slidably mounted in said case, in a position whereby they may be placed in register with said opening or concealed within said compartment, a key actuated lock, and a pivotal member actuated thereby and having locking pins engageable with each of the panels for securing the same in a set position.

6. A display cabinet comprising a case having a display opening formed therein, a compartment in said case adjacent the display opening and in communication therewith, a plurality of vertically disposed panels slidably mounted in the cabinet, guides formed in the cabinet whereby the panels may be optionally placed in register with the display opening or concealed within said compartment, a recess formed in the bottom of each panel, a key controlled lock having a keeper, a pivotally mounted trigger member engaging said keeper and adapted to be actuated thereby, locking pins carried by the keeper and adapted to engage the recesses in the bottom of the panels when said lock is actuated, to maintain said panels in a set position.

GROVER C. POLSON.
